UNITED STATES PATENT OFFICE.

MARY J. DARLING, OF PROVIDENCE, RHODE ISLAND.

TOWEL-RACK.

1,113,880.

Specification of Letters Patent.

Patented Oct. 13, 1914.

Application filed October 7, 1913. Serial No. 793,912.

To all whom it may concern:

Be it known that I, MARY J. DARLING, a citizen of the United States, residing at Providence, in the county of Providence and 5 State of Rhode Island, have invented new and useful Improvements in Towel-Racks, of which the following is a specification.

This invention relates to towel racks and the principal object of the invention is to 10 provide a towel rack of the ordinary spider type which may be converted into a holder for two or more roller towels.

Further objects of the invention will appear as the following description is read in 15 connection with the accompanying drawing, which forms a part of this application, and in which:—

Figure 1 is a side elevation. Fig. 2 is a 20 top plan view showing in dotted lines the position of the arms when used as a spider rack. Fig. 3 is a section on the line 3—3 of Fig. 2. Fig. 4 is a detail vertical section.

Referring more particularly to the drawing, 1 represents a suitable base which may 25 be secured to the wall or other support and has pivotally mounted thereon a substantially W-shaped block 2 which is by reason of its shape provided with slots 3 across which extends the common pivoting pin 4. 30 Pivots mounted upon this pin are the two towel supporting arms 5 which have free movement from the vertical to the horizontal, being thus arranged to secure an operative position and an inoperative position 35 which places the arms out of the way when not in use. Removably mounted upon the outer end of the arms 5 is a connector 6 which joins the two arms and prevents relative movement between the two. By removing 40 this connector and turning the block into parallel position with the support the arms

may be turned horizontally for a quarter of the complete circuit. In other words, they 45 may be drawn back against the wall or turned outwardly straight from the wall.

When the block is in horizontal position the arms are supported in horizontal position at right angles thereto by means of the bottom walls of the notches which constitute supporting shoulders 7. The bolt 8 which pivotally connects the support to the block may be tightened so as to hold the block stationary with the support, and, as shown, each arm is preferably provided with a sleeve 9 which rotates thereon so that 50 when the arms are arranged for roller towels there will be no friction between the towel and the arm.

What is claimed is:—

1. A towel rack comprising a support, a 60 block pivoted upon the support and having limiting shoulders thereon, towel supporting arms pivoted to the block and adapted to engage said shoulders and a connector removably engaged with the outer ends of the arms and adapted to prevent relative movement therebetween.

2. A towel rack comprising a support, a 65 block pivoted upon the support and having limiting shoulders thereon, towel supporting arms pivoted to the block and adapted to engage said shoulders, a connector removably engaged with the outer ends of the arms and adapted to prevent relative movement therebetween and sleeves rotatably mounted upon 70 the arms.

In testimony whereof I affix my signature in presence of two witnesses.

MARY J. DARLING.
